UNITED STATES PATENT OFFICE.

SIDNEY PARHAM VAUGHN, OF ACKERMAN, MISSISSIPPI, ASSIGNOR TO THE SURFACE COMBUSTION COMPANY, INCORPORATED, OF TOLEDO, OHIO, A CORPORATION OF NEW YORK.

METHOD OF BURNING GASEOUS MIXTURES.

Application filed November 7, 1927. Serial No. 231,668.

This invention relates to means and method for developing radiant heat by burning explosive gaseous mixtures while in contact with a refractory surface.

In prior methods of burning explosive gaseous mixtures where combustion takes place on the surface of a permeable refractory bed at normal rates of combustion and the products of combustion are allowed to pass through the bed, an increase in the rate of combustion will force the zone of combustion into the refractory bed and reduce the amount of radiant heat thrown off from the impact surface, and where an explosive gaseous mixture is forced through a porous and permeable refractory diaphragm and combustion allowed to take place on the exit side of the diaphragm, the zone of combustion is localized on the exit side by a fixed rate of combustion. Moreover, if the rate of combustion drops, the combustion zone of the mixture recedes into the refractory bed and if the rate of combustion is increased there will be a blow off. In either case there is a decrease in the amount of radiant heat thrown off from the radiating surface. In my invention the zone of combustion is confined to the surface of the refractory bed regardless of the rate of combustion and thus the highest possible heat radiating efficiency is obtained for all rates of combustion.

In accordance with the present invention explosive gaseous mixture is directed along the line of curvature of a combustion bed having a concaved surface and is caused to burn while moving along the surface of the bed. The bed therefore becomes intensely hot and gives forth radiant heat. The surface of the combustion bed is preferably provided with corrugations extending parallel with the line of curvature of the bed in order among other things that the flow of the gases may be confined to individual paths. The grooves thus formed are preferably made relatively deep and narrow in order to more rapidly retard the velocity of the explosive mixture to a point corresponding to that of flame propagation in the mixture and the ridges are preferably made relatively narrow in order to more quickly become incandescent.

For a more complete understanding of the invention reference is made to the detailed description taken in connection with the ac-

companying drawings forming part of this specification.

Referring to the drawings,

Fig. 1 is a cross sectional view of a furnace embodying the principles of my invention.

Fig. 2 is a perspective view of an open heating apparatus embodying my invention, parts being broken away.

Fig. 3 is a cross section taken on line 3—3 of Fig. 1 and illustrating one form which the grooves and ridges may take.

Fig. 4 shows a modified form of corrugated surface of the combustion bed.

Fig. 5 is an elevation of the combustion bed surface shown in Fig. 1 and showing how the grooves preferably increase in width in a direction away from the place where the combustible gases are initially introduced into the grooves, the view being a fragmentary portion between lines 3—3 and A—A of Fig. 1.

In the furnace shown in Fig. 1, the walls of the heating chamber are generally indicated at 10 and the chamber is shown as substantially circular in cross section. However, such showing is merely for illustrative purposes. The chamber walls beyond the initial curvature at the bottom chamber or above the line 3—3, for example, may be straight if desired, without departing from the spirit of the invention. The interior walls of the chamber form a combustion bed against which the explosive gaseous mixture burns. Projecting through a longitudinally extending opening in the bottom of the chamber is a tube 12 leading from a combustible mixture supply chamber 14. From the tube 12 the mixture is directed in opposite directions against the lower curved part 16 of the combustion bed. The mixture thus impinged against the curved surface flows upwardly and begins to burn where the velocity of the mixture equals that of flame propagation in the mixture, the products of combustion issuing from the chamber through a suitable flue or opening generally indicated at 18. Inasmuch as the mixture burns against the combustion bed, the bed becomes incandescent and constitutes a source of radiant heat for heating the chamber.

The means associated with the tube 12 for directing the explosive gaseous mixture

against the combustion bed may take any suitable form. In the form shown in Fig. 1, the top of the tube is open, and in relatively closely spaced relation therewith is a longitudinally extending flat block 20. Through the space between the block and the top of the tube, the explosive mixture issues with a velocity sufficient to prevent back flash as will be readily understood. This block may also 10 serve as the bed of the heating chamber and may be laterally extended into proximity with the combustion bed as shown. The tube 12 connects with the supply chamber 14. As 15 a means for supplying the supply chamber 14 with explosive gaseous mixture, there has been shown a gas supply pipe 22 having a restricted orifice which discharges into a Venturi tube 24 connected with the supply chamber. The gas in passing into the Venturi tube entrains air as will be readily understood.

While it is preferable to burn a perfect explosive gaseous mixture, it will be understood that the quantity of combustion supporting 25 gas may be varied to suit conditions. For instance, it may be desirable to direct a relatively rich mixture into the combustion bed and depend upon the jet entraining enough air in the vicinity of the combustion bed to 30 complete combustion. To this end the opening in the bottom of the chamber may be larger than the outside diameter of the tube as indicated at 26.

The combustion bed in addition to being 35 curved where the combustible mixture is impinged thereagainst is also formed with a corrugated surface, the grooves or channels and ridges extending in parallelism with the line of curvature. The channels are indicated at 28 and the ridges at 30. The channels are preferably relatively deep in order not only to better confine the combustible mixture to well defined paths of flow but also 40 and primarily by frictional action to more effectively reduce the velocity of the injected mixture to that at which propagation of inflammation will take place. As the fuel burns the ridges will become highly heated and thus 45 accelerate combustion and radiate freely the heat of the fuel. The cross sectional shape of the ridges may vary from those having parallel sides to those having outwardly converging sides as shown in Figs. 2 and 4, respectively. The inverted V-shaped form of 50 ridge offers a stronger construction and may be more desirable for that reason but on the other hand a parallel-walled ridge offers a somewhat better flow channel for the gases. Due to the fact that the velocity of the gases 55 decreases the farther they get from their original point of entry, the flow channels 23 may gradually widen out in the direction of flow to allow a freer upward flow of the products of combustion. In such case the parallel-sided ridges will gradually decrease in

thickness (see Fig. 5,) without necessary decrease in height and the thinner sections will remain substantially as hot or hotter as their thicker sections notwithstanding that the burnt gases are beginning to cool.

A furnace having a heating chamber whose side walls constitute sources of radiant heat is a very desirable form of furnace as will be readily appreciated and my invention offers a simple and practical construction for such 70 a furnace. For some classes of work it may not be entirely practical to make the heating chamber fully circular in cross section but where circumstances permit such form is much to be desired as the heat from the combustion bed side walls is then radiated onto the work from all sides.

Fig. 2 shows how my invention may be embodied in an open type of heating apparatus. The combustion bed 10' has a lower 75 curved part 16' and channels 28' and ridges 30' corresponding to the parts 16, 28 and 30 in the furnace construction already described. This combustion bed 10' also shows how the upper part of the ridges may be extended forwardly with respect to the bottom of the channels in order among other things to provide a more pronounced flue construction 10' for the upwardly flowing products of combustion, it being noted that the upper 90 part of the combustion bed as determined by the bottom of the groove is shown as straight. The means for directing the combustible gases into the grooves may conveniently take the form of a lipped tube 12' connected with 100 a supply pipe 32 leading from a suitable source of supply of combustible gaseous mixture as will be readily understood.

As already indicated the principles of this invention may be embodied in various forms 105 of heating apparatus, and I therefore intend no limitations on the invention except as may be expressed in the appended claims.

What is claimed is:

1. The method of burning explosive gaseous mixtures, which consists in driving the mixture with a velocity greater than the rate of propagation of inflammation through the mixture against the surface of a corrugated combustion bed and parallel with the corrugations therein, whereby the mixture is caused to enter the grooves of the corrugations and its flow velocity reduced by friction to the rate of propagation of inflammation, and burning the mixture in the grooves of the corrugations.

2. The method of burning explosive gaseous mixtures, which consists in causing the mixture to flow with a velocity greater than the rate of propagation of inflammation through the mixture and then reducing the velocity to the rate of propagation by causing the mixture to flow against the surface of a corrugated combustion bed and parallel with the corrugations therein, and burning

the mixture in the grooves and on the ridges of the corrugated surface.

3. The method of producing radiant heat, which consists in combining a fuel in a finely divided state with a combustion supporting gas in proportions to form an explosive gaseous mixture, driving the mixture at a velocity greater than the rate of propagation of inflammation through the mixture against

the surface of an incandescent corrugated combustion bed and parallel with the corrugations formed therein, reducing the velocity to the rate of propagation of inflammation by frictional contact with the corrugated surface, burning the mixture while in contact with the corrugated surface. 10 15

In testimony whereof I affix my signature.
SIDNEY PARHAM VAUGHN.
